UNITED STATES PATENT OFFICE.

JOSIAH CORVEN RODGERS, OF JUNCTION CITY, KANSAS, ASSIGNOR OF ONE-THIRD TO CHARLES K. RABER AND ONE-THIRD TO HARRY PIERCE, BOTH OF JUNCTION CITY, KANSAS.

OIL AND STEAM BURNER.

1,033,037.

Specification of Letters Patent.

Patented July 16, 1912.

Application filed September 15, 1911. Serial No. 649,466.

To all whom it may concern:

Be it known that I, JOSIAH CORVEN RODGERS, citizen of the United States, residing at Junction City, in the county of 5 Geary and State of Kansas, have invented certain new and useful Improvements in Oil and Steam Burners; and I do declare the following to be a full, clear, and exact description of the invention, such as will enable others skilled in the art to which it 10 pertains to make and use the same.

This invention is a burner for consuming a fuel consisting of vapor and steam, and the object of the same is to construct a 15 burner of this character in such way that water and oil admitted thereto will be converted into steam and vapor, and mixed, and then ejected over the pan-shaped body of the burner itself, so that the burning of this 20 mixture generates the steam and vapor and keeps up a constant supply thereof. This object is carried out by constructing the burner in the manner hereinafter more fully described and claimed, and as shown in the 25 drawings wherein—

Figure 1 is a perspective view of the pan or burner proper, and Figs. 2 and 3 are respectively a plan and a side view showing how this pan or burner is connected with the 30 inlet pipe.

The burner forming the subject matter of the present invention includes a flat pan 10 about an inch thick and thirty inches long, and a surrounding rim 11 extending from 35 the inner or flat end 12 of the pan, along its edge, around its rounded end 13, and along its other edge. The pan and its rim are by preference cast entirely of one piece of metal, the rim inclosing a pipe 16 which by preference is made of a single piece so that there 40 will be no elbows or joints within the casting. I have found by experience that a generator pipe made of parallel arms connected by a loop as shown, will successfully 45 resist the excessive heat generated so that this part of the device will not burn out.

In Figs. 2 and 3 of the drawings which show my preferred manner of connecting up this pan for use in an ordinary range or 50 other structure, water is admitted through

an inlet pipe 6 and valve 7 to one end of the generator pipe 16, in which it passes around within the rim 11 of the pan and wherein the water is converted into steam; and the other end of this pipe 16 is connected as at 55 8 with one arm of the head 21 of a T-shaped coupling whose other arm 25 forms a nozzle and is directed along over the center of said pan 10. Oil is admitted through an inlet pipe 4 and valve 5, and flows thence 60 into the inner end of a vaporizer pipe 17 which stands above and is looped around over the rim 11 of the pan in a manner well shown in the drawings. During its passage through this pipe the oil is converted 65 into vapor, and the other end of the pipe is connected through the pipe 20 with the stem of the T-coupling 21 as shown. It follows from this arrangement that water admitted through the pipe 6 and valve 7 and oil ad- 70 mitted through the pipe 4 and valve 5 both flow around the pan—one within the generator pipe 16 where it is converted into steam, and the other through the looped pipe 17 where it is converted into vapor— 75 and these fluids are mixed within the T-coupling and ejected through the nozzle 25 down and along the center of the pan 10, where they burn with an intense heat which not only creates steam and vapor out of the 80 inflowing liquids but gives off this heat in the stove or range or other device within which the burner is located. The latter may be attached to an ordinary furnace or range by merely laying it upon the grate, or re- 85 moving the latter and supporting the pan upon the grate support, proper connections being made with the oil and water pipes in a manner which is not necessary to illustrate and describe. It will possibly be de- 90 sirable to provide for cleaning and flushing out the pipes at times so as to prevent them from becoming clogged or fouled.

What is claimed as new is:

The herein described pan having one end 95 rounded, its upper face being flat except for a raised rim around said end and along its edges, a looped steam-generating pipe contained within said rim, a valved connection between one end thereof and a source of wa- 100

ter supply, a second looped oil-vaporizing pipe standing above said rim, a valved connection between one end thereof and a source of oil supply, and a mixer connected with 5 the other ends of said pipes and having its nozzle directed toward the rounded end of the pan and the bends in said pipes.

In testimony whereof I have hereunto set my hand in presence of two subscribing witnesses.

JOSIAH CORVEN RODGERS.
